Primary Examiner — Susan B Hattan*Assistant Examiner* — Leanne Was-Englehart(74) *Attorney, Agent, or Firm* — Sean O'Connell, PLLC(57) **CLAIM**

The ornamental design for a door seal with fins, as shown and described.

DESCRIPTION

FIG. 1 is an isometric view of the door seal with fins.

FIG. 2 is an end view thereof.

FIG. 3 is a right side elevation view thereof.

FIG. 4 is a left side elevation view thereof.

FIG. 5 is a plan view of the door seal with fins; and,

FIG. 6 is a bottom view thereof.

The portion of the article between the break lines forms no part of the claimed design.
